UNITED STATES PATENT OFFICE.

AUGUSTUS M. SOSA AND ALBERT E. ROBINSON, OF CINCINNATI, AND HERMAN W. SCHATZ, OF NORWOOD, OHIO, ASSIGNORS TO THE AMERICAN TOOL WORKS COMPANY, OF CINCINNATI, OHIO, A CORPORATION OF OHIO.

FEEDING MECHANISM FOR METAL-WORKING MACHINERY.

1,351,969.

Specification of Letters Patent. Patented Sept. 7, 1920.

Application filed October 23, 1917. Serial No. 198,034.

To all whom it may concern:

Be it known that we, AUGUSTUS M. SOSA, ALBERT E. ROBINSON, and HERMAN W. SCHATZ, citizens of the United States, the 5 said HERMAN W. SCHATZ residing at Norwood, in the county of Hamilton and State of Ohio, and the said ALBERT E. ROBINSON and AUGUSTUS M. SOSA residing at Cincinnati, in the county of Hamilton and State of 10 Ohio, have jointly invented certain new and useful Improvements in Feeding Mechanism for Metal-Working Machinery, of which the following is a specification.

Our invention relates to feeding means 15 for axially feeding a tool-spindle in metal working machinery; to means for determining the extent of axial movements of the tool-spindle and for duplications of said movement; and to a safety stop for the feeding means.

Our invention relates further to a so-called tapping attachment for controlling the axial feeds of the tool-spindle in connection with its rotations for cutting threads.

25 We have exemplified our invention as applied in a drilling machine embodying a rotatable axially movable drill-spindle.

It is the object of our invention to provide novel means for combinedly rotating 30 and axially feeding a tool-spindle for performing thread-cutting operations; further, to provide novel means for axially feeding the tool-spindle; further, to provide novel means for selectively controlling the coöperation of 35 the tool-spindle with the thread-cutting means or with the feeding means; further, to provide novel means for connecting and disconnecting the thread-cutting means with relation to the driving means of the tool- 40 spindle; further, to provide novel means for controlling the extents of axial movement of the tool-spindle, for instance, the axial feeding or thread-cutting movements thereof, to predetermined depths, and for repeating the 45 predetermined axial movements of the tool-spindle; and, further, to novel means for stopping the feeding movement of the tool-spindle when at the limit of its path of movement.

50 The invention will be further readily understood from the following description and claims, and from the drawings, in which latter:

Figure 1 is a front elevation of a drill-

head, exemplifying our invention, shown in 55 connection with a drill-arm, the latter partly broken away.

Fig. 2 is a side elevation of the same.

Fig. 3 is a plan view of the same.

Fig. 4 is a front elevation of the same 60 with the front of the casing and the arm removed.

Fig. 5 is a left side elevation of the same, with the casing of the drill-head and parts partly broken away for better illustration, 65 the casing being partly in vertical section on the line 5—5 of Fig. 1.

Fig. 6 is a similar right side elevation of the same, with parts in axial section, taken 70 on the line 6—6 of Fig. 12.

Fig. 13 is a cross-section taken on the line 90 13—13 of Fig. 4.

Fig. 14 is a vertical section, taken on the line 14—14 of Fig. 13, and showing the 95 means for changing the feeds of the drill-spindle.

Fig. 15 is a horizontal section of the same, taken on the line 15—15 of Fig. 14.

Fig. 16 is an axial section, taken on the line 16—16 of Fig. 4, illustrating the means for controlling the extents of axial movements of the tool-spindle. 100

Fig. 17 is a plan view of the same, partly broken away.

Fig. 18 is a plan section of the same, taken in the plane of the line 18—18 of Fig. 16. 105

Fig. 19 is a cross-section of the same, taken in the plane of the line 19—19 of Fig. 16.

Fig. 20 is a detail in cross-section taken in the plane of the line 20—20 of Fig. 16.

Fig. 21 is a rear elevation of the controlling means for controlling the extent 5 of axial movement of the tool-spindle, partly in section in the plane of the line 21—21 of Fig. 17, and illustrating the dial set at zero.

Fig. 22 is a similar view, illustrating the 10 relation of the parts with the dial set for the limit of feeding movement of one of the 15 divisions of feed.

Fig. 23 is a similar view, with the dial set at a position for the beginning of the 15 second division of feeding movement of the 20 tool-spindle.

Fig. 24 is a similar view, with the dial set for the limit of the second division of 25 feeding movement of the tool-spindle; and,

Fig. 25 is a similar view showing the 20 relation of the parts, with the dial at the position of the tripping moment between the 25 divisions of feed.

We do not herein claim the means for 25 automatically arresting the feeding movements of the tool-spindle, herein shown and described, as the same are shown, described and claimed in an application divisional 30 hereof, Serial No. 277,597; filed by us February 17, 1919.

The present exemplification of our invention is shown as applied to a metal drilling machine, so much of a metal drilling machine being shown as is necessary to illustrate our invention.

A tool-arm 31 has a tool-head 32 laterally slidable thereon on guides 33, in any ordinary or well-known manner, as by means of a hand-wheel 34, which operates a 40 suitable pinion coaxing with a rack 35 extending lengthwise of the tool-arm. The tool-arm is arranged to be raised and lowered on a suitable column in any usual manner. The tool-head has a tool-spindle 37 45 therein.

Suitable means are provided for rotating the tool-spindle, which may be accomplished by means of a shaft 38, (see Figs. 2 and 3), extending lengthwise of the tool-arm and 50 operated in suitable manner from the column of the machine. It is arranged to operate suitable gearing in a housing 41 for selectively rotating a gear 42 on an upright shaft 43 in opposite directions. The gear 42 meshes with a gear 44 fast on a bushing 45 journaled in a bearing 46 in the casing 47 of the tool-head. (See Fig. 4.) The bushing has spline-connection 48 with the spindle for rotating the spindle with the 55 gear, regardless of the elevation or axial movement of the spindle.

A sleeve 51 surrounds the spindle and moves axially in a bearing 52 of the casing. The spindle rotates in the sleeve, and the 60 sleeve is held non-rotatingly in the bearing,

in usual manner, end-thrust bearings 53, 54, being between the sleeve and spindle. The sleeve is provided with a rack 55 with which a pinion 56 engages for feeding the spindle. (See Figs. 4 and 16). The pinion is fast on a shaft 57, journaled in a bearing 58 in the tool-slide, and having a bushing 59 received thereabout, with which it has rotative connection, as by a key 60. The bushing extends from a face-plate 61. 70 A worm-wheel 64 is provided with a hub 65 serving as a bushing, in which the bushing 59 is journaled, the hub 65 in turn being journaled in a bearing 66 in the tool-slide. 75

The face-plate has arms 67 pivoted thereto at 68, for quick positioning of the spindle axially. The arms are articulated at 69 with an axially movable stub shaft 70 having a cam-key 71 thereon, arranged to engage a lever 72 for actuating a friction-band 73 of a friction-clutch for fixing the worm-wheel 64 and face-plate 61 together, when it is desired to feed the spindle by means of the worm-wheel. The friction-band 73 is moved radially by operation of any one 80 of the operating levers 67 outwardly for engaging the clutch, any one of said arms being movable inwardly for disengaging the clutch to manually move the drill-spindle axially, the clutch being operated by 85 any one of said arms which may be within most convenient reach of the operator, in the same direction, for producing a given result.

The pinion 56 is arranged to be rotated 100 by means of the worm-wheel or by means of the face-plate, and the worm-wheel is arranged to be rotated manually or by a plurality of speed-varying devices, one of which comprises a so-called tapping attachment, and the other of which is a feeding device, means being provided for selectively and independently connecting the tapping attachment or the feeding device with the worm-wheel, and further means being provided for disconnecting the tapping attachment from its operating means during disconnection of the tapping attachment from the spindle, so as to cause the tapping attachment to remain in a state of rest during 105 the times that the tapping attachment is not actually in use, so as to prevent wear of the parts. Extreme accuracy is required in a tapping attachment, so that predetermined axial feed of the spindle with relation to speed of rotation thereof may be maintained throughout substantially the life of the machine for maintaining accuracy in the machine throughout a long period of time when cutting threads or performing similar duties.

Instancing the means for performing these duties, co-operating nests of gears 75, 76, are provided. The nest of gears 75 comprises gears of different diameters ar- 130

ranged stepwise and fixed to a shaft 77 journaled in bearings 78 of the casing. (See Figs. 4, 5, 6, 11 and 12.) The nest of gears 76 comprises gears of different diameters arranged stepwise oppositely to the gears of the nest of gears 75 and meshing with the latter.

The bushing 45 about the spindle is provided with a gear 79 fast thereon. A stud-shaft 80 is fixed in a bearing 81 of the casing and extends upwardly. (See also Fig. 7). It has a sleeve 82 thereabout, which is arranged to be moved axially by means of a fork 83, the tines of which are received 15 in an annular groove 84 in said sleeve. The fork is fixed to an axially movable rod 85, slideable endwise in a bearing 86, and having a rack 87 thereon. The rack is engaged by a pinion 88 cut in a shaft 89, journaled 20 in a bearing 90 of the casing, and having a hand-wheel 91 fixed thereon, the hand-wheel extending outside the casing for manually moving the sleeve.

A gear 95 is fast with the sleeve 82 and 25 is arranged to mesh the gear 79 about the spindle. A pinion 96 is also fast with the sleeve and is arranged to mesh with the upper one of the gears of the nest of gears 75. The sleeve 82 is normally in upward 30 position, and when in such position its gear 95 is out of mesh with the gear 79, and its pinion 96 is out of mesh with the upper one of the nest of gears 75. When it is desired to use the tapping attachment, the hand-wheel 91 is turned for causing descent of said 35 sleeve, which causes meshing of the gear 95 with the gear 79, and of the pinion 96 with the upper gear of the nest of gears 75, for rotating said nest of gears in definite 40 relation to the speed of rotation of the spindle.

The gears of the nest of gears 76 are normally loose about a bushing 101, rotatable in bearings 102 of the casing. An axially movable rod 103 is slideable in the bushing, 45 and has a retractable key 104, hereinafter referred to as a pivoted key, the key being pivoted in a slot 105 in said rod. The bushing is provided with a slot 106 extending lengthwise thereof, and the respective gears 50 of the nest 76 are provided with key-slots 107. The pivoted key is normally urged toward said key-slots by means of a spring 108 secured to the rod 103 and movable therewith. Disengaging rings 109 are located in 55 annular grooves 110 between the proximate gears of the nest of gears 76. The rings are arranged to disengage the key from the slots in the gears when moving the key lengthwise, so as to prevent engagement of the key 60 with more than one gear at a time. The ends of the key may be provided with inclined faces 111 for aiding in the disengagement.

The speed of transmission of the tapping 65 attachment is determined by the gear with

which the key engages, four different speeds of transmission being instanced, which speeds may be multiplied a suitable number of times by means of any suitable speed varying devices acting on the spindle, or in 70 any other suitable manner.

The rod for the pivoted key is provided with an annular rack 112, with the teeth of which a pinion 113 engages, the pinion being fast on a shaft 114 journaled in a bearing 115 of the casing, and having a hand-wheel 116 thereon, an index-plate 117 being fast with said hand-wheel and arranged to 75 coact with a pointer 118 on the outside of the casing for indicating the gear with 80 which the pivoted-key engages at any given position of the hand-wheel, or the speed conveyed thereby. (See Figs. 4, 5, 6, 11, 11^a and 12.) A gear 121 is fixed to the bushing and meshes with a gear 122 fixed to a shaft 85 123 journaled in bearings 124 in the casing, and having a gear 125 fast thereon (see Figs. 5, 6, 11 and 12). The gear 125 meshes with a gear 126 rotatable on a stud-shaft 127 fixed in a bearing 128 of the casing. (See 90 Figs. 6, 12 and 13.)

The means for feeding the spindle axially are exemplified as a pair of nests of gears 131, 132, the gears of which normally rotate loosely respectively about bushings 133, 95 134, journaled in bearings 135, 136, in the drill-head. (See Figs. 4, 5, and 14.) A gear 137 meshes with a gear 138 rotating with the drill-spindle, being shown as fixed to the bushing 45 about the drill-spindle. 100 (See also Fig. 13.)

A gear 141 is provided with a hub 142 journaled in the upper bearing 135. The gear 137 is fixed to the hub 142 as by a screw 143. The bushing 133 is journaled in the 105 bore of said hub. Sets of gears 145, 146 and 147, are loosely journaled about the bushing 133, each of the sets of gears comprising a larger gear and a smaller gear, fixed together as by a key 148. A gear 149 110 is fixed to the bushing. The sets of gears are located between the combined gears 137, 141 and the gear 149. Rings 151 are located in annular grooves 152 between the proximate sets of gears and between the sets of 115 gears and the combined gears 137, 141 and gear 149.

The bushing 133 is provided with a slot 154 extending lengthwise thereof, and the hub 142 and the respective sets of gears are 120 provided with key-slots 155. A retractable key 156, shown as a pivoted key, is pivoted at 157 in a slot 158 of an axially movable rod 159. It is arranged to be normally pressed into coaction with the key-slots 155 by a 125 spring 161 fixed to the axially movable rod. When the pivoted key is in engagement with hub 142, the bushing 133 is caused to rotate with the hub, and when the pivoted key is in engagement with one of the gears, the bush- 130

ing is caused to rotate with the set of gears so engaged, for transmitting variable speeds to the gear 149. The ends of the pivoted key are provided with slanting faces for ready disengagement from the key-slots when engaging the rings.

Sets of gears 165, 166, 167, are journaled normally loose about the bushing 134, and an additional gear 168 is also journaled normally loose about said bushing. The sets of gears respectively comprise a smaller gear and a larger gear, fixed together. Rings 169 are located in annular grooves 170 between said sets of gears, and at the respective ends of said group of sets of gears. A gear 171 is fixed to the bushing 134 and meshes with the gear 149. The gear 171 also meshes with a gear 172 rotatable on a stud-shaft 173, fixed in a bearing 174 of the casing. The gear 172 is located in substantial endwise relation with the gear 126.

The bushing 134 is provided with a slot 175, extending lengthwise thereof, and the respective sets of gears 165, 166, 167, and the gear 168, are provided with key-slots 176.

A retractable key 178, shown as a pivoted key, is pivoted at 179 in a slot 180 of an axially movable rod 181. It is arranged to be normally pressed into coaction with the key-slots in the sets of gears, by means of a spring 182 fixed to the axially movable rod. When the pivoted key is in engagement with one of the sets of gears or the gear 168 about the bushing 134, it is caused to rotate with the bushing, for transmitting the speed of rotation thereof through the bushing to a gear 171 fixed to said bushing. The slot 175 is extended beyond the sets of gears so that the pivoted key 178 may be moved into idle relation with all the gears about the bushing 134.

The ends of the pivoted key 178 are provided with slanting faces for ready disengagement of the same from the key-slots when engaging the rings.

In the present exemplification of our invention, the sets of gears about the bushing 133 and the sets of gears about the bushing 134 each comprises a gear of larger diameter and a gear of smaller diameter, the sets of gears about the respective bushings being placed in lapping relation, so that the gears of larger diameter of the sets of gears about the bushing 133 mesh with the gears of smaller diameter of the sets of gears about the bushing 134, and vice versa, the upper end one of the group of sets of gears about the bushing 134 being meshed by the gear 141, and the lower end one of the group of sets of gears about the bushing 133 being meshed by the gear 168.

The gear 137 is exemplified as the driving gear, and rotates with the gear 141, which meshes with the larger gear of the set of gears 165, transmitting rotation to said set

of gears, which in turn transmits rotation at a diminished speed to the set of gears 145, decreasing speeds of rotation being successively transmitted to the sets of gears 166, 146, 167, 147, the set of gears 147 rotating 70 the separate gear 168.

The speeds of the single gears and of the respective sets of gears are different, so that if motion is transmitted from any one of said single gears or sets of gears to the respective bushings, the result will be a given speed, and if motion is transmitted through any other of said single gears or sets of gears to said respective bushings, the result will be a different speed.

The gears about the respective bushings 133 and 134 are arranged to be selectively alternately connected with said respective bushings, means being provided so that if connection is made between one of the bushings and a gear or set of gears thereabout, the engagement between the pivoted key of the other of said bushings and the gear or sets of gears thereabout is automatically released, and vice versa. For this reason the sets of gears about the respective bushings are arranged in lapping relation to each other, and the rings about the respective bushings are also arranged in off-set relation to each other, so that when one of the pivoted keys is caused to engage a key-slot, this engagement can take place only during disengaged relation of the other of said pivoted keys with all key-slots coacting therewith.

Means are also provided for simultaneously actuating the pivoted-keys, instanced as comprising a hand-wheel 185 fixed to a shaft 186 journaled in a bearing 187 of the casing, an index-plate 188 being fixed to rotate with said hand-wheel, the indicating marks thereon being caused to register with a coacting pointer 189 on the outside of the casing. The shaft 186 has a bevel-gear 190 thereon, which meshes with a bevel-gear 191 fixed to a shaft 192 journaled in bearings 193 of the casing, and having pinions 194, 195, thereon which respectively mesh with annular racks 196, 197, on the respective rods 159, 181. A finger 198 on the shaft 186 coacts with a stop-pin 199 on the bearing 187 to limit turning of the shaft 186 to maintain the circular racks in engagement with the pinions.

When now the hand-wheel 185 is turned to move the axially movable rods 159, 181, both the pivoted-keys will be moved axially with the rods. Assuming that the pivoted-key 156 engages the key-slot in gear 141, the transmission of motion will be from the gear 137 through the hub 142, which transmits motion to the bushing 133, this bushing transmitting motion to the gear 149 fixed thereon, which meshes with the gear 171, and in turn rotates the gear 172. The rest of the gears of the nests of gears run idle.

By this means a feed which may be instanced as .040 inches per revolution of the drill-spindle may be obtained. If it is desired to change the ratio of axial feed of rotation of the drill-spindle, exemplified as a decreasing feed, the pivoted-keys are simultaneously caused to descend, by operation of the hand-wheel 185, for engaging the pivoted-key 178 with the key-slot of the set of gears 165, whereby the transmission of motion is through the gear 137, the hub 142, the gear 141, and the set of gears 165, which act on the key 178 for rotating the bushing 134, which rotates the gear 171 and in turn rotates the gear 172, resulting in a feed instanced as .029 inches per revolution of the drill-spindle.

Other desired changes may be had by causing further axial movement of the rods 20 on which the pivoted-keys are mounted, for obtaining, for instance, successively .022, .016, .012, .009, .007, and .005, inches in the feeding movement of the drill-spindle per revolution of the same.

25 In the present exemplification, eight different speeds of axial feed of the drill-spindle may be obtained, by means which take up little space and are easily operated, and the speeds of which are changed without 30 danger of locking of gears or of parts that might result in breakage of elements. The speeds obtained may be multiplied by speed varying means varying the speed of the drill-spindle.

35 The gear 126 is the power-delivering gear of the tapping attachment, and the gear 172 is the power-delivering gear of the feeding mechanism. There is a space 201 between said gears. The gears 126, 172, are arranged 40 to be selectively meshed by a gear 202 having spline-connection 203 with a shaft 204 journaled in a bearing 205 in the casing. (See Figs. 4, 5, 6, 13 and 14.) The gear 202 is arranged to be moved axially, as by having a hub 206 thereon, which has a sleeve 207 thereabout in which the hub is journaled. The sleeve slides axially in a bearing 208. The sleeve is fixed axially with relation to said gear by being received about

50 said hub between the gear proper and a collar 209 fixed to the hub. The sleeve is provided with a slot 211 lengthwise thereof, in which a pin 212 received through the bearing of 55 the sleeve is received. A pinion 213 meshes with the rack, and is on a shaft 216 journaled in a bearing 214 of the casing and has a hand-wheel 215 thereon for turning the same.

60 When the hand-wheel is turned in one direction, the gear 202 will be caused to be disengaged from the gear 172 and to engage with the gear 126, causing the tapping attachment to be in train with the feed-shaft 204. When the hand-wheel is turned in the

opposite direction, the gear 202 is caused to disengage from the gear 126 and to engage with the gear 172, for causing the speed varying means of the feeding attachment to be in train with said feed-shaft 204.

70 The shaft 204 is arranged to operate a worm 218, which meshes with the worm-wheel 64, through the medium either of the tapping attachment gears, or of the feeding gears. (See Figs. 4, 8 and 16.) The worm 75 is also arranged to be operated by manual means, instanced as accomplished by means of a hand-wheel 219 fixed to a shaft 220, journaled in a bearing 221 of the casing, the shaft being held lengthwise in said bearing between said hand-wheel and a collar 222 fixed to said shaft. The lower end of the shaft 204 is journaled in a bore 223 in the worm. The shaft 204 is held lengthwise in a bearing 205 between collars 224, 225, 80 fixed to said shaft, the collars 224, 225, engaging the bearing 205.

85 If it is desired to operate the worm by hand, the shaft 204 is disconnected from the worm 218. This is accomplished by 90 means of a clutch 226, shown as a tooth-clutch, the teeth being respectively on the worm and on a collar 227, having spline-connection 228 with the shaft 204. A fork 229 is received in annular groove 230 in 95 said collar, and is fixed to a rock-shaft 231 journaled in a bearing 232 of the casing, and having an operating arm 233 secured thereto.

100 It is often desirable to cause repeated axial movements of the tool-spindle to given extents, for instance when tapping threads, or boring holes, the extents of these axial movements sometimes varying greatly. These axial feeds by the tapping attachment and by the feeding means, are accomplished in the present exemplification by means of the worm 218 and worm-wheel 64. The worm wheel acts on the pinion 56 for 105 rotating the same and feeding the spindle 110 axially. It may be instanced that a single revolution of the pinion 56 will feed the tool-spindle approximately six inches.

115 It often happens that a greater axial feed than is accomplished by an approximately single rotation of the pinion, is desired. Means are provided in the present exemplification for causing stoppage of the axial feed at any point during a single rotation of the worm-wheel, or pinion, or during a 120 plurality of said rotations. The stoppage of the feed, in the present exemplification, is accomplished by disengagement of the clutch 226.

125 For accomplishing these purposes, I provide the index-plate with a plurality of indexes 237, 238, instanced as on an index-ring 239 adjustable with relation to the pinion and index-plate. (See Figs. 4, 16 and 17.) The ring in the present instance 130

is rotatable on a journal-face 240 of the body of the index-plate, and is arranged to be clamped in adjusted radial positions thereon by means of a clamp, which comprises a stem 242 axially movable in a bearing 243 of the body of the index-plate, and having a shoe 244 thereon, the clamping face of the shoe coacting with an annular inclined face 245 at the rear of the index-ring, which latter is clamped against an annular flange 246 on the body of the index-plate. The outer end of the stem is screw-threaded, for having threaded engagement made therewith by a handle 247. A thimble 248 surrounds said stem, a spring 249 being in the bore of said thimble about said stem, for urging release between the clamp and the index-ring.

The rear face of the index-ring is provided with a knock-off shoe 251 and with a tripper-pin 252, the tripper-pin being instanced as projecting rearwardly farther than the knock-off shoe. (See Figs. 16, 17, 18, and 21 to 25 inclusive.)

25 A sleeve 253 has axial movement in a bearing 254 of the tool-head, and has a rack 255 thereon, which engages a segment rack 256, on a segment-arm 257, secured to the rock-shaft 231. This rock-shaft is the shaft 30 which has the operating arm 233 and the fork 229 thereon, the fork engaging the clutch-collar 227 of the clutch 226, for engaging or disengaging the clutch. The segment-arm is provided with a pin 261 fixed therein, the pin being provided with an apex 262 formed by oppositely sloping faces. A pin 263 is axially movable in a bore 264 in the tool-head and is moved toward the pin 261 by means of a spring 265. 40 The pin 263 is provided with an apex 266 formed by oppositely sloping faces, the apices 262 and 266 coacting with each other and their opposed sloping faces, for causing quick completion of the engagement or 45 disengagement of the clutch when the apex 262 has passed the apex 266.

When the segment-arm has been moved sufficiently to cause the opposed sloping faces on the pins to relatively slide, so as 50 to bring the apices of the respective pins into line, a slight further movement of the segment-arm will cause coaction of the opposite faces of said apices and a quick rocking movement of the segment-arm in its 55 moving direction for either engaging or releasing the clutch 226 with a quick movement.

60 The sleeve 253 has an axially movable and rockable shank 269 therein. This shank is provided with a gage-finger 270, which is provided with an index-mark or marks, a plurality of the index-marks being provided when a plurality of the indexes on the index-ring are employed. Thus the finger 65 is provided with an index-mark 271,

which coacts with the index 237, and with an index-mark 272, which coacts with the index 238. It also has a handle 273 thereon for moving the shank. The shank is journaled in a bearing 274 of the casing and in 70 the bore 275 of sleeve 253. It has a collar 276 thereon which is fixed thereto, as by a pin 277, the collar being provided with a shoe 278, eccentric on the collar. The shoe 278 is shown as having an outer curved, 75 face upon which one of the inclined faces of the shoe 251 is arranged to ride, the parts being so arranged that when the apex of the shoe 251 coacts with the outermost point on the shoe 278, the apex 262 will register 80 with the apex 266, so as to cause the apex 262 to pass across the apex 266 at the moment of correlation between the apices of the shoes 251, 278, whereby the clutch 226 is instantly disengaged, for stopping the 85 rotation of the feeding means for the tool-spindle.

In the present exemplification, the outer index is caused to index during a single revolution of the pinion 56, this outer index being instanced as indexing depths of feed of the tool-spindle from zero to six inches. Throughout this range of feeds, rotary movement of the shank 269 is not required, in fact the shank might be dispensed with 95 and the shoe 278 fixed directly to the part carrying the segment-rack 255.

If it is desired to repeat axial movement of the tool-spindle of a given extent or depth, the tool-spindle is in practice fed 100 axially to a given point, exemplified, for instance, by the point of engagement of the point of the tool 280 with the surface of the work, instanced at 281, the axial feeding of the tool being then stopped. (See Fig. 2.) 105 The index-ring is then unclamped from the body of the index-plate and rotated, for instance by grasping the finger-knob 282 thereon, until the index-mark 271 registers with the mark on the index 237, which indicates the desired depth of cut or axial movement of the tool-spindle, whereupon the clamp is again operated for clamping the index-ring to the body of the index-plate for causing the index-ring to move 115 with the body of the index-plate. This movement is in the direction of the arrow *a*.

The feeding of the drill into the material is then begun, the index-plate, including its ring, rotating with the pinion 56 and the worm-wheel 64, until the zero mark on the index 237 registers with the index-mark 271, at which moment the apex of the shoe 251 registers with the apex of the shoe 278, and the apices 262, 266, of the pins 261, 263, are 125 at the point of passage to cause quick tripping movement of the segment-rack by means of the springs and consequent disengagement of the clutch 226. The operation may thereupon be repeated as many times 130

as desired without change of relation in the index means, for again causing a similar feeding movement at the same portion of the axial movement of the tool-spindle.

5 If it is desired to obtain an axial movement of the tool-spindle greater than the circumferential pitch line of the pinion 56, the index 238 is employed, the point of the tool being again brought to contact-position 10 on the work. The index-ring being unclamped, it is turned until the desired depth of cut or axial movement of the tool-spindle is indicated on the inner index 238 in line with the index mark 272, whereupon the index-ring 15 is again clamped to the body of the index-plate. The handle 273 is then moved outwardly and turned to cause an axial and a rocking movement of the shank 269. The collar 276 is provided with a 20 tongue 283 which normally lies in a groove 284 in an enlargement 285 of the sleeve 253. The axial movement of the shank 269 moves the collar and sleeve forwardly into the position shown in Fig. 17. The rocking movement 25 of the shank causes the tongue to lie crosswise of the groove, the collar and handle being turned into the assumed positions shown in Figs. 23 and 24. This turning of the shank also moves the shoe 278, which is 30 eccentrically placed on the shank, out of the path of the shoe 251.

Fig. 23 indicates the position and relation of the parts of the knock-off shoe and pin when the feed is set for example at a depth 35 to correspond to the beginning of the markings of the inner index, instanced as a feed of 6.001 inches.

In Fig. 24 the parts and the relation of the shoe and pin are indicated to represent 40 a maximum feed within the capacity of the inner index, and is instanced as a feed of a depth of twelve inches.

The collar is provided with a tripper-finger 287. When the index is set for an indication requiring more than one revolution 45 of the index-plate to trip the clutch in order to cause cessation of feeding movement, the pin 252 will, at approximately the first arrival of the zero mark of index 237 at the index-mark 271, strike the finger 287 and cause rotation of the collar 276, and the shank 269, for placing the shoe 278 in the path of the shoe 251, this relation of parts 50 being shown in Fig. 25, it being understood that when the said collar has been rocked, as shown in Figs. 23 and 24, that the shoe 55 278 is out of registry with the path of movement of the shoe 251. When the index-plate completes its final rotation, the shoe 60 251 will coact with the shoe 278, and thereby move the shank 269 inwardly and cause inward movement of the rack 255 for rocking the segment-rack 256 and disengaging the clutch 226.

It will be noted that there is a space 289 65 between the zero mark and the highest mark on the outer index, and a space 290 between the lowest mark and the highest mark of the inner index. These spaces represent the difference between the pitch-line circumference of the pinion 56 and a whole number. Thus, if a complete revolution 70 of the pinion 56 represents an axial travel of the tool-spindle of a fraction more than six inches, the spaces represent the 75 fraction, which forms a gap in the index, the gap being compensated by the space 291 between the index-marks 271, 272, which would represent the angular travel of the 80 index-plate through said fractional space, the angular distance between the index-marks 271, 272, bridging said spaces 289, 290.

The shank is provided with a screw 292 which is slideable in a slot 293 in the rack-sleeve, the slot having a portion which is parallel with the axis of the shank, and a portion which is at right angles thereto, the relations of the parts being preferably such that the axially extended relation of the 90 shank and sleeve is maintained by contact of the head of the screw with the right angular portion of the wall of said slot, for relieving the frictional engagement between the tongue of the collar and the outer 95 face of the enlarged portion of the rack-sleeve. A spring 294, the ends of which are respectively secured to pins 295 and 296, respectively in a bore 297 of the shank and the bore 275 in said rack-sleeve, normally 100 draws the shank inwardly.

Safety means are also provided for stopping the axial feed of the tool-spindle. (See Figs. 8, 9 and 10.) Thus the rock-shaft 231 is provided with a bore 301 in which a 105 rod 302 is axially movable. The rack-sleeve of the spindle is provided with a bracket 303 having a cam-face 304 thereon. The rod has a pin 305 fixed therein transversely thereof. The pin is fixed to a collar 309 slideable on the rock-shaft 231. The pin slides in a slot 306 in the rock-shaft and is arranged to impinge a cam-face 307 on a cam-block 310 fixed to the drill-head, when the rod 302 is moved axially by the cam-face 304, which occurs when the drill-spindle has reached its desired lowermost limit of movement, whereby the shaft 231 is rocked by movement of the pin 305 along the cam-face 307, for disengaging the clutch 110 226 and stopping the feed of the spindle. A spring 308 normally urges the rod 302 toward the cam-face 304.

It is obvious that changes may be made in the exemplifications hereinbefore described within the scope of the appended claims, without departing from our invention. 125

Having thus fully described our invention, what we claim as new and desire to secure by Letters Patent, is:

1. In a metal drilling machine, the combination of a drill-spindle, means for rotating the same, a gear rotating with said drill-spindle, a variable speed gearing arranged for operative connection with said drill-spindle for feeding the same axially, 10 a pair of axially movable gears arranged for connection respectively with said first-named gear and said variable speed gearing, and means for moving said pair of gears axially out of coactive relation with 15 said first-named gear and said variable speed gearing and into coactive relation with the same.

2. In a metal drilling machine, the combination of a drill-spindle, means for rotating the same, a pair of gears received about and rotating with said drill-spindle, a pair of nests of gears of different diameters and a driven gear, a pair of nests of gears of 20 different diameters and a driven gear, 25 means for axially feeding said spindle comprising a driving gear arranged to be selectively meshed with said respective driven gears, and an axially movable gear for causing operative connection between one of 30 said first-named gears about said drill-spindle and said first-named pair of nests of gears and release of said driving connection, the other of said first-named gears having 35 operative connection with said second-named pair of nests of gears.

3. In metal working machinery, the combination of a tool-spindle, and feeding means for said tool-spindle comprising a plurality of nests of gears respectively comprising a plurality of sets of gears respectively composed of gears of different diameters connected for rotating together, said sets of gears of said respective nests of gears arranged in axial alinement, said sets of 40 gears of said collective nests of gears operatively connected in offset relations lengthwise of the axes of said nests of gears for transmitting different speeds to one another, and means causing driving relation 45 selectively in said respective nests of gears.

4. In metal working machinery, the combination of a tool-spindle, and feeding means for said tool-spindle comprising a plurality of nests of gears respectively comprising sets of gears composed of gears of different diameters connected for rotating together, said sets of gears of said respective nests of gears arranged in axial alinement, said sets of gears of said collective nests of 55 gears operatively connected in offset relations in directions lengthwise of the axes of said gears for transmitting different speeds to one another, connecting means for each of said nests of gears, diverting means therefor, and means for simultaneously axially 60

moving said connecting means, said diverting means in said respective nests of gears arranged in offset relation.

5. In feeding mechanism of the character described, the combination of a tool-spindle, 70 means for rotating said tool-spindle, and means for axially feeding said tool-spindle comprising a plurality of nests of gears, said respective nests of gears comprising sets of gears of different diameters, the sets of gears 75 of said nests of gears arranged in axially offset relation for causing driving connection between said sets of gears of different nests of gears, and simultaneously movable means for causing operative relation in said 80 respective nests of gears.

6. In feeding mechanism of the character described, the combination of a tool-spindle, and means for axially feeding said tool-spindle comprising a plurality of nests of 85 gears, said respective nests of gears comprising sets of gears of different diameters rotating together, said sets of gears of each of said nests of gears arranged in axial alinement, the sets of gears of said collective 90 nests of gears arranged in offset relations in directions lengthwise of the axes of said gears for causing driving connection between said sets of gears of different nests of gears, and simultaneously movable means 95 alternately connecting with the sets of gears of different nests of gears for transmitting different speeds.

7. In feeding mechanism of the character described, the combination of a tool-spindle, 100 means for rotating said tool-spindle, and means for axially feeding said tool-spindle comprising a pair of nests of gears each comprising sets of gears the gears of which are of different diameters, the sets of gears 105 of said collective nests of gears having meshing relation with each other for transmitting different speeds of rotation progressively from one to the other of said sets of gears of said respective nests of gears, and means causing operative connection with said respective sets of gears alternately in 110 said respective nests of gears.

8. In feeding mechanism for metal working machinery, the combination of a tool-spindle, and means for axially feeding said tool-spindle comprising a pair of bushings, sets of gears of different diameters the gears whereof are connected together, said sets of gears journaled about said respective bushings and arranged in offset meshing relations progressively in directions lengthwise of the axes of said gears, simultaneously axially movable means in said bushings alternately connecting said respective bushings selectively with the sets of gears thereabout, and means for transmitting the resultant speed into axial feeding movement of said tool-spindle. 115

9. In feeding mechanism for metal work- 130

- ing machinery, the combination of a tool-spindle, and means for axially feeding said tool-spindle comprising a pair of bushings, a plurality of sets of gears each composed of 5 gears of different diameters journaled about said respective bushings and relatively arranged in offset meshing relations in directions lengthwise of the axes of said gears, a pair of axially movable rods in said bushings, means for simultaneously axially moving said rods, and means moved by said respective rods alternately connecting said respective bushings with a selective one of 10 the sets of gears thereabout.
- 15 10. In feeding mechanism of the character described, the combination of an axially feedable tool-spindle, a plurality of bushings, nests of gears, each of said nests of gears comprising sets of gears of different 20 diameters journaled about said respective bushings and arranged relatively in axially offset meshing relation, axially movable rods in said respective bushings, means for simultaneously axially moving said rods, connecting means for said respective rods selectively connecting said respective bushings and the respective sets of gears thereabout, said last-named means including means for 25 causing simultaneous connection in one of 30 said nests of gears and freedom of connection in another of said nests of gears, and means operatively connecting one of said elements with said tool-spindle for axially feeding the same.
- 35 11. In feeding mechanism of the character described, the combination of an axially feedable tool-spindle, a pair of bushings, nests of gears about said respective bushings, said respective nests of gears comprising 40 axially alined sets of gears composed of gears of different diameters, said sets of gears of said nests of gears arranged in axially offset meshing relation, gears at opposite ends of said respective nests of gears 45 having meshing relation with the respective end ones of the sets of gears of the other of said nests of gears, said gears normally rotatable about said bushings, means causing operative connection alternately between 50 said respective bushings and the gears normally rotatable thereabout, and a gear fixed to each of said bushings, said last-named gears having meshing relation, constructed and arranged for transmitting selective 55 speeds of feed to said tool-spindle.
12. In feeding mechanism of the character described, the combination of a tool-spindle, and means for axially feeding said tool-spindle comprising a pair of nests of 60 gears, each of said nests of gears comprising a series of sets of gears of different diameters in axial alinement with each other, the sets of gears of said nests of gears arranged in relatively offset meshing 65 relation for transmitting motion alternately to the sets of gears of said respective nests of gears, a bushing for each of said nests of gears about which the gears thereof are normally rotatable, an axially movable rod in each of said bushings, a retractable key 70 for each of said rods, means for causing alternate coaction of said respective retractable keys with the gears of said respective nests of gears, each of said axially movable rods provided with a circular rack, a pinion 75 meshing with each of said racks, and means for simultaneously rotating said pinions for simultaneous axial movement of said rods.
13. In feeding mechanism of the character described, the combination of a tool-spindle, and means for axially feeding said tool-spindle comprising a pair of bushings, sets of gears of different diameters rotatable together arranged in axial alinement normally loose about said respective bushings, 80 said sets of gears about said respective bushings arranged in axially offset meshing relation, a single gear normally loose about each of said bushings, said single gears located at the respective ends of said sets of 85 gears about said respective spindles, and simultaneously movable means in each of said bushings for connecting said bushings selectively with said respective gears thereabout, said last-named means acting alternately for 90 forming said connections, and means to transmit various speeds to axially feed the tool-spindle.
14. In feeding mechanism of the character described, the combination of a tool-spindle, a pair of bushings, a nest of gears about each of said bushings, each of said nests of gears comprising sets of gears of different diameters arranged in axial alinement and a single gear at opposite ends of 100 said sets of gears, said sets of gears of said nests of gears arranged in offset meshing arrangement with said single gears meshing with the offset ones of said sets of gears at the respective ends of said respective nests of gears, means for selectively connecting said respective sets of gears and said single gears with said respective bushings, a gear fixed to each of said bushings and having meshing relation with each 105 other, and driving means between one of said gears and said spindle for axially feeding said spindle at selective speeds determined by said connections with said respective bushings.
15. In a drilling machine, the combination of a drill-spindle, means for rotating the same, variable speed gearing comprising a driven gear, means for selectively rotating said variable speed gearing, variable speed 110 gearing comprising a driven gear located below said first-named driven gear, a feed-shaft having operative connection with the drill-spindle for axially feeding the same, a gear thereabout having operative connec- 115
- 120
- 125
- 130

- tion with said feed-shaft, and means for axially moving said last-named gear axially of said feed-shaft into meshing relation selectively with said respective driven gears.
- 5 16. In a drilling machine, the combination of a drill-spindle, means for rotating the same, variable speed gearing, comprising a driven gear, means for selectively rotating said variable speed gearing, variable speed 10 gearing comprising a driven gear, said last-named driven gear located below said first-named driven gear and spaced therefrom, a feed-shaft having operative connection with said drill-spindle for axially feeding the 15 same, a gear about said feed-shaft for driving the same, said gear comprising a hub, a sleeve in which said hub is rotatable, said sleeve having a rack thereon, a pinion meshing with said rack, and an operating handle 20 therefor for moving said last-named gear axially selectively into mesh with said respective spaced apart driven gears.
17. In feeding mechanism for metal working machinery, the combination of a tool-spindle, a plurality of nests of gears arranged for transmitting various speeds alternately from a gear of one of said nests of gears to a gear of another of said nests of gears a plurality of times in crossing 25 relation, a plurality of lengthwise shiftable members comprising means connecting alternately with the gears of said respective nests of gears for transmitting said speed changes, and a single manual means having 30 operative connection with each of said lengthwise shiftable members, and means for converting said speeds into axial feeding movement of said tool-spindle.
- 35 18. In feeding mechanism for metal working machinery, the combination of a tool-spindle, and means for axially feeding said tool-spindle comprising a pair of bushings, sets of gears of different diameters journaled about said respective bushings, the 40 gears of said sets of gears alternately meshing with each other for rotating said gears of successive sets at progressively different speeds, lengthwise movable means in said respective bushings for connecting said respective bushings alternately with the gears 45 of said respective sets of gears, a single manual operating part connecting with both said 50

lengthwise movable means for combinedly operating the same, and means for transmitting the resultant speed into axial feed- 55 ing movement of said tool-spindle.

19. In feeding mechanism for metal working machinery, the combination of a tool-spindle, and means for axially feeding said tool-spindle comprising a pair of bushings, 60 nests of gears of different diameters journaled thereabout, the gears of said respective nests of gears meshing with one another to transmit progressively varying speeds, means comprising an axially movable member in each of said bushings for selectively alternately connecting the gears of said respective nests of gears with said respective bushings, and means for combinedly moving said last-named means for alternately connecting the gears of said respective nests of gears and said bushings. 65

20. In a drilling machine, the combination of an axially feedable tool-spindle, a rack-sleeve therefor, a pinion for the latter, a worm-wheel for driving said pinion, a rotatable part having connection with said pinion, a friction-clutch comprising a radially movable friction-part between said rotatable part and said worm-wheel, and 70 means for moving said radially movable friction part comprising a lengthwise movable actuating part, and a plurality of operating levers pivoted to said rotatable part and having operative connection with said lengthwise movable actuating part for moving said lengthwise movable actuating part in one direction by manual movement of either of said respective operating levers inwardly and for moving said lengthwise movable actuating part in opposite direction by manual movement of either of said respective operating levers outwardly, said operating levers rotatable with said rotatable part. 75

In testimony whereof, we have hereunto 80 signed our names in the presence of two subscribing witnesses.
